UNITED STATES PATENT OFFICE.

BERTRAM G. WORK, OF AKRON, OHIO.

DESIGN FOR A WATER-BOTTLE STOPPER.

SPECIFICATION forming part of Design No. 27,623, dated September 7, 1897.

Application filed June 21, 1897. Serial No. 641,715. Term of patent 14 years.

To all whom it may concern:

Be it known that I, BERTRAM G. WORK, a citizen of the United States, residing at Akron, in the county of Summit and State of Ohio, have invented and produced a new and original Design for Water-Bottle Stoppers, of which the following is a specification, reference being had to the accompanying drawings, forming part thereof, in which—

5 Figure 1 is a side view, and Fig. 2 an edge view, of a water-bottle stopper showing my new design.

As shown in the drawings, the leading feature of my design consists of a rounded base

A, surmounted by a projecting fleur-de-lis ornamentation B. The parts may be left plain or, it is manifest, they may be engraved, chased, or otherwise ornamented, as desired.

Having described my invention, what I claim as new, and desire to secure by Letters 20 Patent, is—

The design for a water-bottle stopper, as herein shown and described.

BERTRAM G. WORK.

In presence of—

J. W. KELLEY,
J. F. PALMER.
